UNITED STATES PATENT OFFICE

JOHN A. McGREW, OF ALBANY, NEW YORK

RAIL JOINT

Application filed November 6, 1928. Serial No. 317,608.

This invention relates to rail joints and more especially to rail joints of the type used in connection with standard railroad rails.

It is a general object of the present invention to provide a novel and improved type 5 of rail joint.

More particularly it is an object of this invention to provide a rail joint in which the abutting ends of the rails are supported by girder action from the adjacent cross-ties.

10 One of the features of the invention consists in the provision of a joint member adapted to be received in the fishing space of adjoining rails, which member has its 15 upper surface so formed that but a small portion of its center engages the underside of the rail heads, and in which the lower face is so formed that only the end portions thereof engage the upper faces of the rail bases whereby the abutting ends of the rails 20 are supported in girder fashion from those portions of the rail bases which rest on cross-ties.

Other and further features and objects of 25 the invention will become more apparent to those skilled in the art after a consideration of the accompanying drawings and following specification wherein there is disclosed a single exemplary embodiment of the invention. It is to be understood that this embodiment is for purposes of disclosure only and is not to be construed as limiting the invention except in accordance with the scope 30 of the appended claims.

35 In said drawing:

Figure 1 is a plan view of a pair of rails joined according to the present invention;

Figure 2 is a side elevation thereof;

40 Figure 3 is a transverse section taken on line 3-3 of Fig. 2 near the end of the joint;

Figure 4 is a central transverse section taken on line 4-4 of Fig. 2; and

Figure 5 is a diagrammatic showing of the fundamentals of the invention.

45 It has been the practice for a number of years to join the abutting ends of railroad rails by the use of fish plates or similar splice members arranged in the fishing space between the under surface of the rail heads and the upper surface of the rail bases, and to bolt 50

these splice bars, one on either side of the web, tightly together so that they have a wedging action in the fishing space, thus securing the two rails together and tending to form a continuous beam or girder of the same. 55 It is customary to have the rail ends abut midway between a pair of cross-ties, and reliance is placed on this continuous beam effect to support these ends. The static load and the dynamic load resulting from pounding, particularly of the counterweights of locomotive drivers, is such that splice bars of this type not only do not remain tight but are seriously worn as a result of movement between them and the rails.

65 Experience shows that it is improper to attempt to so splice a pair of rail ends that, in effect, the two rails become a continuous girder. The present invention contemplates the use of splice bars which of themselves 70 form a girder substantially supported from adjacent cross-ties and holding the rail ends supported on its upper surface. The splice bar thus becomes, in effect, a simple beam or girder supported at the ends and carrying 75 a load midway of its length.

75 Referring to the drawings, the invention is seen to be applied to the ends of a pair of rails 10 of standard form having the heads 11 with the fishing surfaces 12 and bases 13 80 with the fishing surfaces 14, one fishing surface at the upper edge and one at the lower edge of the web 15. The rail ends substantially abut as shown at 16, leaving merely 85 sufficient space for expansion and contraction due to temperature changes. The rail ends are secured together by splice bars on fish plates 17, which are largely housed within the fishing spaces of the rails. These splice bars are adapted to be held in position by the bolts 18 passing through their vertical webs and through the web of the rail and fastened with nuts 19 and lockwashers in the standard manner.

90 Referring now particularly to Figure 5, which is wholly diagrammatic, the mode of operation of the splice bars may better be understood. The single bar shown is formed so that its upper surface engages beneath the rail heads on the surface 12 only between the 95 100

points 21 and 22. The distance between these points is considerably less than 25% of the full length of the splice bar. The remaining portions of the upper surface of the splice bar are relieved as shown at 23 so as to clear the fishing surface 12. The bottom of the splice bar is relieved intermediate its ends as at 24 to clear the fishing surface 14, and only the end portions of the bottom surface 14 of the splice bar engage the fishing surface 14 as shown at 25.

Since it is always customary to have the joint between the rails intermediate a pair of cross-ties such as 26, and since the distance between ties is more or less standard with each railroad, the length of the splice bars can be made such that the surfaces 25 are substantially directly above the cross ties 26. This results in the splice bar acting as a simple beam supported from the cross-ties over the areas 25 and supporting the rail ends only between the points 21 and 22 which is substantially at the center of the splice bar.

It will be seen that this type of joint is based on the improved principle, of carrying the wheel loads over the rail joints by girder action in the joint rather than by splice action, as is at present the case. Splice joints, as previously stated, attempt to obtain a continuous girder effect at the ends of the rails. In the present design the three-point contact of the splice bar does not reinforce the ends of the rails but supports the extreme ends and transfers the resulting wheel loads at the ends through the splice bar acting as a girder to the adjacent supporting cross ties.

As clearly seen in Figures 3 and 4, the cross sections of the splice bars are of special form to increase their strength against longitudinal bending. For instance, each has a large head 30 with the re-enforcing side rib 31 and comparatively thin web 32 formed by relieving the inner face as shown at 33. The bottom of each splice bar is the portion which takes the tensile load, and it is flattened and widened as shown at 34 and provided with the inner rib 35 and the outer rib 36. The outer face of the web portion is flat as shown at 37 to receive the fastening means. The portions 34 can be notched as shown at 38 to receive spikes or other means for fastening the joint to the cross-ties, and, of course, tie-plates as shown at 39 may be used, as is conventional.

Referring to Figure 2, it will be seen that the side rib 31 is straight, and that its upper surface merges with the upper surface of the splice bar at the ends, but that portion 60 of the splice bar which extends under the rail heads extends up and narrows to the engaging face 40, as shown at 41. The ends of the bottom surface 42 of the wing portions 34 engage the upper surface of the rail base 65 only in an area directly beneath the rail head,

as clearly seen in Figure 3, whereas the remaining portion is spaced away from the rail base as shown at 44. This section, of course, represents the arrangement at the ends of the splice bar, whereas in Figure 4 the center portion thereof shows a full clearance 45 between the under surface of the wing portion and the upper surface of the rail base.

It is believed that from the showing and the above description the fundamental features and the resulting different mode of operation of the invention will be readily apparent.

Having thus described the invention, what is claimed as new and desired to be secured by Letters Patent is:

1. In a rail joint, the combination with aligned meeting rails having heads, webs and bases, of joint plates each formed with a central portion to engage under substantially the full width of the rail heads beyond the webs at only the ends thereof, said plates having lower flanges overlying substantially the whole width of the rail bases, the ends only of said flanges engaging said bases, and only on the area beneath the rail heads, each plate having an intermediate portion extending substantially the full length thereof and out of engagement with the rail webs.

2. In a rail joint, the combination, with aligned meeting rails having heads, webs and bases, of joint plates each formed with a head having a surface to engage the rail heads only at the ends thereof, a flange on each plate at the bottom thereof wider than the rail base flange and engaging the same only at the ends of the plate flange, an intermediate portion between said head and flange out of engagement with said web, the major portion of the metal of each plate being in the head and flange to enhance the beam action thereof.

In testimony whereof I hereunto affix my signature.

JOHN A. McGREW.
